UNITED STATES PATENT OFFICE.

MICHAEL LUTHER, OF BRIDGEPORT, CONNECTICUT.

DESIGN FOR AN ICE-CREEPER.

SPECIFICATION forming part of Design No. 32,441, dated April 3, 1900.

Application filed January 23, 1900. Serial No. 2,545. Term of patent 7 years.

To all whom it may concern:

Be it known that I, MICHAEL LUTHER, a citizen of the United States, and a resident of Bridgeport, in the county of Fairfield and State of Connecticut, have invented a certain new and original Design for Ice-Creepers, of which the following is a specification.

In the drawings, Figures 1 and 2 show, respectively, inside and outside perspective views of an ice-creeper embodying my novel design.

As shown in the drawings, the leading or material feature of my design consists in the graceful shape and features of a creeper, the same comprising a plate having a shield-shaped opening therein and the front and side edges of which are provided with an upwardly-disposed continuous flange, the further and general outlines of said creeper corresponding substantially to that of the heel of a shoe.

The plate A is provided with a central shield-shaped opening B, as clearly appears

in the drawings. The under side of the plate contains a series of spikes C, having tapering points, as shown. A continuous and upwardly-disposed flange D is provided on the forward and the two side edges of the plate. The inside portion of this flange crossing the forward end of the plate contains a pair of spikes E E, the pointed ends of which are deflected inward. At the rear of the plate is an upwardly-disposed lug F, which contains a screw-hole G, as shown.

Having thus described my invention, what I claim, and desire to secure by Letters Patent, is—

The design for an ice-creeper, as herein shown and described.

Signed at Bridgeport, Fairfield county, Connecticut, this 17th day of January, A. D. 1900.

MICHAEL LUTHER.
